UNITED STATES PATENT OFFICE.

MOSES MOSLER, OF CINCINNATI, AND CARL BARTELS, OF HAMILTON, OHIO, ASSIGNORS
TO THE MOSLER SAFE COMPANY, OF NEW YORK, N. Y.

SAFE CONSTRUCTION.

1,136,254.

Specification of Letters Patent.

Patented Apr. 20, 1915.

Application filed November 25, 1914. Serial No. 873,875.

To all whom it may concern:

Be it known that we, MOSES MOSLER, a citizen of the United States, residing at Cincinnati, Hamilton county, Ohio, and CARL BARTELS, a citizen of the United States, residing at Hamilton, Butler county, Ohio, have invented certain new and useful Improvements in Safe Construction, of which the following is a specification.

10 This invention, pertaining to safe-construction, and in referring to safes we intend the comprehension of vaults as well, relates to the system by means of which the door of the safe is drawn tightly to its seat in the jamb when the door is being closed and forced out of the seat in the jamb when the door is to be opened, the mechanism for accomplishing these results serving as a pressure-bar device for forcing the door to 15 and away from its seat in the jamb or, if desired, serving also as means for locking the door of its seat.

Our invention will be readily understood from the following description taken in connection with the accompanying drawings in which:—

Figure 1 is a front elevation of the front of the safe with the door closed, the upper left-hand corner of the door being broken 30 entirely away to expose jamb-features, and the lower portion being shown in vertical section in the plane of line *b* of Figs. 2, 4 and 5. Fig. 2, a vertical section of the structure in the plane of line *a* of Figs. 1 and 3, the major portion of the edge of the door appearing in elevation: Fig. 3, a front elevation of a portion of the system of toothed bars carried by the door: Fig. 4, a horizontal section of the door-jamb and 35 door in the plane of line *c* of Figs. 1, 2, 3 and 5, the door being shown separated from the jamb but in position to be pushed into the jamb: Fig. 5, an elevation of the teeth in the jamb at the left side of Fig. 1 and 40 viewed from the right in Fig. 1, combined with a vertical section of the coöperating locking teeth of the door, the section being taken in the plane of line *d* of Figs. 1, 3 and 4, the locking teeth of the door being in position corresponding with the unclosed condition of the door, that is to say, the door 45 is yet to be closed into its jamb by a motion in the direction of the arrow *i*, the same as in Fig. 4; and Fig. 6, a plan of the 50 toothed locking bar carried by the left-hand

edge of the door. Diverse scales are employed in the drawings.

In the drawings: 1, indicates the front of the safe; 2, the stepped door-opening therein; 3, a toothed bar rigidly secured in the jamb, there being one of these bars at each margin of the jamb, the bar being provided at intervals with inwardly projecting teeth, the bar being merely an expedience for securing the teeth in the jamb; 4, the door; 5, the stepped margin of the door adapted to tightly fit the jamb; 6, hinge-bearings upon the door and safe, adapted to receive the usual crane-hinge; 7, a groove in each of the marginal edges of the door and extending 60 the general length of the margins, though not necessarily connecting at the corners of the door; 8, a toothed-bar fitted to slide in each of these marginal grooves and prevented from displacement therefrom by any suitable means, slots and cross-pins being illustrated for the purpose, each of these bars being provided at intervals with outwardly projecting teeth adapted to pass through the 65 spaces between the teeth of the jamb when the door is being closed; 9, a shive mounted at each corner of the door in the plane of these toothed bars; 10, chains passing over these shives and connecting the contiguous 70 ends of bars 8 in such manner that when one of the bars is shifted endwise, a corresponding endwise shifting of all the other bars must take place; 11, a rack provided on the inner edge of one of bars 8, preferably the 75 edge farthest from the hinge-bearings carried by the safe front; 12, a spindle journaled in the door near the rack and accessible from the front of the door, so that it may be turned; 13, a pinion on the rear end of these spindles, engaging the rack on the toothed bar; 14, a pivoted locking-dog mounted near pinion 13 and having a toe 80 normally out of engagement with the pinion but adapted to engage a shoulder on the periphery of the pinion and prevent the pinion 85 from turning in a certain direction; 15, a lock-connection from the locking-dog and adapted to be connected in any suitable manner with the lock or locks of the door, regardless of whether the locks be combination 90 locks or time locks or both; 16, the knobs of usual combination locks on the door, to serve in controlling the locking-dog; 17, the inwardly projecting locking teeth of the 95 jamb; 18, the outwardly projecting locking 100 teeth of the door; 19, a lock-connection from the locking-dog and adapted to be connected in any suitable manner with the lock or locks of the door, regardless of whether the locks be combination locks or time locks or both; 20, the knobs of usual combination locks on the door, to serve in controlling the locking-dog; 21, the inwardly projecting locking teeth of the 105 jamb; 22, the outwardly projecting locking 110 teeth of the door.

teeth of the door, these teeth being carried by sliding-bars 8; 19, slight bevels on the front surfaces of the door-teeth 18; 20, corresponding bevels on the rear surfaces of the jamb-teeth; 21, beveled hooks projecting from some of the jamb-teeth toward contiguous jamb-teeth, the bevels of these hooks being in the same direction as the bevels of teeth 20 but at much greater angle; 22, beveled hooks projecting from some of the door-teeth 18 toward contiguous door-teeth, these hooks being opposite jamb-hooks 21; and 23, bevels on the front corners of some of the door-teeth and on the rear corners of coöoperating ones of the jamb-teeth, these bevels being in the same direction as the bevels upon the front of the door-teeth and upon the rear of the jamb-teeth, but at greater angle.

Generally stated, when the door is pushed into its jamb the teeth 18 of the door pass through the spaces between the teeth 20 of the jamb and take position to their rear, after which spindle 12 is turned causing a simultaneous endwise movement of all of the door-bars 8 thus causing the door-teeth to slide behind the jamb-teeth, the coöperating bevels on these teeth drawing the door solidly to its seat in the jamb. The safe-locks whatever be their character may cause dog 14 to lock the pinion so as to prevent releasing movement of the door-teeth. Under these conditions the system would have acted as a pressure device to force the door solidly to its seat, and as a locking device to prevent the door being unseated.

In all of the figures of the drawings the door-teeth are indicated in unlocked position, that is to say, while the door has been pushed to closed position, it may be freely opened. In Fig. 5 and in Fig. 4 the door elements are indicated as not yet having entered the jamb. Looking at Fig. 5, understand that teeth 18 are sliding teeth carried by the door. Upon pushing the door to the right as indicated by arrow *i* the door-teeth 18 will pass between the jamb-teeth 17 and take position to their rear. This motion will be arrested when the bevels of the door-hooks 22 strike the bevels of jamb-hooks 21. When this occurs, still looking at Fig. 5, the door-teeth must move downward somewhat, which motion brings bevels 23 in engagement and forces the door farther into its jamb, with quickness but not powerfully. A continued downward motion of the door-teeth causes their bevels 19 to coöperate with the bevels 20 on the jamb-teeth, thus forcefully seating the door solidly in the jamb, and locking the door to the jamb if the toothed door-bars be under the control of the safe-locks. Still looking at Fig. 5, when the safe is to be opened, the toothed door-bar is raised, the safe locks, if in action, having been first released. The first effect of the

rising of door-teeth 18 is to release the pressure between bevels 19 and 20, without necessarily unseating the door from its jamb. But when the rising motion of the door-teeth causes the bevels of door-hooks 22 to engage the bevels of jamb-hooks 21, then the door becomes forced away from its seating in the jamb and, the upward motion of the door-teeth having been completed, the door is at liberty to be opened.

Looking at Figs. 1 and 3, indicating the door-teeth 18, as in released condition, the turning of pinion 13 in counter-clockwise direction will move the left-hand toothed-bar in the direction of arrow *e*, the lower toothed-bar in the direction of arrow *f* the right-hand toothed-bar in the direction of arrow *g* and the top-bar in the direction of arrow *h*. By this motion of the bars, carried to the proper extent, the door has been forced solidly to its seat. If, now, the safe-locks be put on duty, the locking dog 14 prevents the retracting motion of the pinion and the door is not only solidly seated in its jamb, but is locked.

In the illustrated example the toothed-bars of the door are provided with teeth at short intervals. There may be as many of these teeth as desired, for purposes of tight seating of the door and for purposes of security, the thinner the door the greater being the desirability for a number of the teeth disposed along intermediate portion of the door-bars, with, of course, corresponding teeth in the jamb. But it is obvious that the door-bars may have teeth near their ends only, their intermediate portions being toothless and correspondingly as to the teeth in the jamb. For instance, looking at Fig. 5, the door-bar might, if desired, be provided at its upper end with only the hooked tooth, and the jamb with only the hooked tooth and the tooth below it. In such case there would be produced the result of urging the door to its jamb, and then forcing it solidly to the jamb and locking the door in its jamb and, when the door was to be opened, forcing the door out of its seating in the jamb.

We claim:—

1. Safe-construction comprising, a stepped rectangular door-jamb having teeth projecting inwardly from sides of the jamb, a door having a stepped margin fitting the door-jamb, grooves in the edges of the door to the rear of the plane of the teeth in the door-jamb, a bar fitted for endwise motion in each of said grooves, teeth projecting from the outer edges of said bars and adapted to pass rearwardly through the spaces between the teeth of the door-jamb while the door is being closed and to be slid behind the teeth of the jamb by the endwise movement of the bars, means for preventing the bars from lateral displacement from their grooves, de-

vices operatively connecting all the bars so that they will take on endwise motion in unison, and mechanism accessible from the exterior of the door for shifting said bars, combined substantially as set forth.

5 2. Safe-construction comprising, a stepped rectangular door-jamb having teeth projecting inwardly from the sides of the jamb, a door having a stepped margin fitting the door-jamb, grooves in the edges of the door to the rear of the plane of the teeth in the door-jamb, a bar fitted for endwise motion in each of said grooves, teeth projecting from the outer edges of said bars and adapted to pass rearwardly through the spaces between the teeth of the door-jamb while the door is being closed and to be slid behind the teeth of the jamb by the endwise movement of the bars, the rear faces of the teeth in the jamb being beveled and the front faces of the teeth of the door-bars being correspondingly beveled to engage and force the door firmly to its seat after the door-bars have partaken of a portion of their sliding motion, means for preventing the bars from lateral displacement from their grooves, devices operatively connecting all the bars so that they will take on endwise motion in unison, and mechanism accessible from the exterior of the door for shifting said bars, combined substantially as set forth.

3. Safe-construction comprising, a stepped rectangular door-jamb having teeth projecting inwardly from the sides of the jamb, a door having a stepped margin fitting the door-jamb, grooves in the edges of the door to the rear of the plane of the teeth in the door-jamb, a bar fitted for endwise motion in each of said grooves, teeth projecting from the outer edges of said bars and adapted to pass rearwardly through the spaces between the teeth of the door-jamb while the door is being closed and to be slid behind the teeth of the jamb by the endwise movement of the bars, the rear faces of the teeth in the jamb being beveled and the front faces of the teeth of the door-bars being correspondingly beveled to engage and force the door firmly to its seat after the door-bars have partaken of a portion of their sliding motion, the beveled surfaces of both sets of teeth being provided with additional and steeper bevels at their preliminarily engaging portions so that the door will be quickly moved toward its seat before being forced firmly thereto, means for preventing the bars from lateral displacement from their grooves, devices operatively connecting all the bars so that they will take on endwise motion in unison, and mechanism accessible from the exterior of the door for shifting said bars, combined substantially as set forth.

65 4. Safe-construction comprising, a stepped

door-jamb having teeth projecting inwardly from the jamb, a door having a stepped margin fitting the door-jamb, grooves in the margin of the door to the rear of the plane of the teeth in the door-jamb, bars fitted for endwise motion in said grooves, teeth projecting from the outer edges of said bars and adapted to pass rearwardly through the spaces between the teeth of the door-jamb while the door is being closed and to be slid behind the teeth of the jamb by the endwise movement of the bars, the rear faces of the teeth in the jamb being beveled and the front faces of the teeth of the door-bars being correspondingly beveled to engage and force the door firmly to its seat after the door-bars have partaken of a portion of their sliding motion, means for preventing the bars from lateral displacement from their grooves, devices operatively connecting all the bars so that they will take on endwise motion in unison, mechanism accessible from the exterior of the door for shifting said bars, beveled hooks upon teeth of the jamb, and beveled hooks upon teeth of the door to cooperate with the hooks of the jamb and force the door from its seat in the jamb when the door-bars are moved in the direction opposite that in which they move to force the door to its seat in the jamb, combined substantially as set forth.

5. Safe-construction comprising, a stepped rectangular door-jamb having teeth projecting inwardly from the sides of the jamb, a door having a stepped margin fitting the door-jamb, grooves in the edges of the door to the rear of the plane of the teeth in the door-jamb, a bar fitted for endwise motion in each of said grooves, teeth projecting from the outer edges of said bars and adapted to pass rearwardly through the spaces between the teeth of the door-jamb while the door is being closed and to be slid behind the teeth of the jamb by the endwise movement of the bars, means for preventing the bars from lateral displacement from their grooves, devices operatively connecting all the bars so that they will take on endwise motion in unison, mechanism accessible from the exterior of the door for shifting said bars, and a locking-dog adapted to connect said mechanism with the safe-lock and prevent the movement of said bars in the releasing direction, combined substantially as set forth.

6. Safe-construction comprising, a stepped rectangular door-jamb having teeth projecting inwardly from the sides of the jamb, a door having a stepped margin fitting the door-jamb, grooves in the edges of the door to the rear of the plane of the teeth in the door-jamb, a bar fitted for endwise motion in each of said grooves, teeth projecting from the outer edges of said bars and adapted to pass rearwardly through the spaces

- between the teeth of the door-jamb while the door is being closed and to be slid behind the teeth of the jamb by the endwise movement of the bars, means for preventing the 5 bars from lateral displacement from their grooves, devices operatively connecting all the bars so that they will take on endwise motion in unison, a rack upon one of said bars, a pinion engaging said rack, and a 10 spindle connected with said pinion and accessible from the exterior of the door to serve in turning the pinion and shifting the bars endwise, combined substantially as set forth.
- 15 7. Safe-construction comprising, a stepped door-jamb having teeth projecting inwardly from the jamb, a door having a stepped margin fitting the door-jamb, grooves in the margin of the door to the rear of the 20 plane of the teeth in the door-jamb, bars fitted for endwise motion in said grooves,
- teeth projecting from the outer edges of said bars and adapted to pass rearwardly through the spaces between the teeth of the door-jamb while the door is being closed 25 and to be slid behind the teeth of the jamb by the endwise movement of the bars, means for preventing the bars from lateral displacement from their grooves, shives carried by the corners of the door near and in 30 line with the contiguous ends of the bars, flexible connectors passing over said shives and connecting the contiguous ends of bars, and mechanism accessible from the exterior of the door for shifting said bars, combined 35 substantially as set forth.
